MANUFACTURE OF TRINITROTOLUENE

Francis Stapleton Chambers, Jr., Woodbury,
N. J., and Clifford Akeley Woodbury, Media,
Pa., assignors to E. I. du Pont de Nemours &
Company, Wilmington, Del., a corporation of
Delaware

No Drawing. Application March 27, 1943,
Serial No. 480,836

3 Claims. (Cl. 260—645)

This invention relates to improvements in the manufacture of trinitrotoluene, and more particularly to the removal of acidity from the crude acid-retaining material.

The manufacture of trinitrotoluene from toluene is conventionally carried out in three stages, wherein mono-, di-, and trinitrotoluene are obtained in successive nitrations using predetermined temperatures and compositions of nitration acids. Only the trinitrocompound requires careful purification since the others are intermediate products in its preparation. Trinitrotoluene is present in the final stage in suspension and partial solution in the spent acid, comprising a blend of sulfuric, nitric, and nitrosyl sulfuric acids along with dissolved nitro bodies. Since the trinitration temperature is above the freezing point of trinitrotoluene, this latter material will be in molten form. After a short period of standing there is a definite line of separation between the molten trinitrotoluene and the spent acid, and this latter can be drawn off.

The molten trinitrotoluene which has been separated from the spent acid retains a certain amount of included acid as well as other impurities. Customarily this molten material is washed repeatedly with successive quantities of hot water and agitated during the washing with intermediate separations of the wash waters. These wash waters are discarded. Because of the relatively high solubility of the trinitrotoluene in hot water, such treatments lower the yield of purified material and at the same time introduce the problem of recovering the dissolved trinitrotoluene from the discarded wash waters. In spite of this loss, this treatment has been considered necessary before in the purification of trinitrotoluene.

It is an object of the present invention to eliminate the necessity for recovering trinitrotoluene conventionally lost during hot water washes and render unnecessary the catch boxes and other apparatus required for such recovery. A further object is an improved process for obtaining a substantially pure trinitrotoluene product from the separated crude material containing retained acid and other impurities. An additional object is the removal of acidity from crude trinitrotoluene. A further object is an improved process for refining trinitrotoluene. Additional objects will be discerned from the following description of the invention:

We have found that the foregoing objects are accomplished and the disadvantages of the prior art methods overcome by separating the molten, newly formed crude trinitrotoluene from the bulk

of the spent acid, adding thereto cooling water having a temperature below the solidification point of the molten crude, to crystallize the latter, and neutralizing by the addition of an alkali such as sodium carbonate. The alkali can be added to the trinitrotoluene either before or after the solidification has occurred. Alternatively, the trinitrotoluene may be crystallized in the presence of the alkali, by adding alkali to the cold water employed to cool and crystallize the trinitrotoluene. The removal of acidity may be effected by any of the foregoing treatments.

After the acidity has been removed, the crude neutralized trinitrotoluene may be used as such, or if desired, a purified product may be obtained by further treatment.

In the event that a purified product is required, the solid particles of neutralized trinitrotoluene preferably are subjected to a surface treatment with a solution of sodium sulfite or other water-soluble inorganic sulfite, preferably a sulfite of an alkali metal.

The following examples will serve as more specific embodiments of the application of our invention and are set forth by way of illustration only and not as limiting in any way.

Example 1

Following the completion of nitration of di-nitrotoluene to trinitrotoluene, separation of the latter material in molten form from the bulk of the spent acid took place at a temperature above 200° F. Approximately 3600 lbs. of the crude trinitrotoluene, thus separated and containing about 35 100 lbs. of retained acid, were treated with approximately 178 gallons of cooling water having a temperature of 70° F. which were introduced gradually with agitation. Crystallization took place at around 160° F. Neutralization of the acid solution by means of sodium carbonate followed, a total of approximately 100 lbs. of sodium carbonate in solid form being added gradually, the end point being indicated by test papers and by a slight brown color of the water. Following the neutralization, 180 gallons of a 16% solution of sodium sulfite were introduced into the mixture for the purpose of washing isomeric and other impurities from the surface of the crystals. The slurry was then pumped to the filter and the crystals washed with large amounts of cold water. The trinitrotoluene obtained by the foregoing process, after suitable drying and granulation was of good quality, having a freezing point of 50 55 80.43° C.

Example 2

The procedure of Example 1 was carried out, with the variation that the neutralization with sodium carbonate was effected while the acid-retaining trinitrotoluene was still in molten form. The same amount of cooling water was then added and crystallization effected. Surface treatment of the crystals with sodium sulfite solution was carried out and the crystals filtered and washed as in Example 1. Agitation was used in the various steps and the same quantities of water, sodium carbonate, and sodium sulfite solution were employed. The product was of excellent quality and good yields of purified crystals were obtained.

In the foregoing examples, the acidity was neutralized by means of alkali; in one case after crystallization, and in the other while the trinitrotoluene was in molten form. It should be understood that our invention includes also the series of steps where the separated molten and acid-retaining trinitrotoluene is crystallized by the addition of cooling water and where the surface acidity on the crystals is removed not by neutralization but by filtration and washing on the filter by a succession of water washes. Such acid-free material can then be reslurried and purified, if desired, by treatment with a water-soluble inorganic sulfite. The losses of trinitrotoluene usually experienced in the processes of the prior art are avoided here, since no hot water washes are given the material with subsequent discarding of hot wash waters. In this connection it should be noted that any hot water present with the molten TNT is not removed but retained while the cooling water is added. Hot water may be present either from the addition of the same to the molten crude, or from flushing of the apparatus.

In the specific embodiments of the operation of our process illustrated in the two examples, sodium carbonate was used for neutralizing the acidity. Other alkalies may be employed however, for example potassium carbonate, sodium or potassium bicarbonate, sodium hydroxide, sodium sulfite, and the like.

The crystals have been described as being given a surface washing with an aqueous solution of sodium sulfite. Such a sulfite solution has the property of dissolving the isomeric forms of the 2,4,6-trinitrotoluene which are present mainly on the surface of the crystals; it has little solvent power, however, for the 2,4,6-isomer. It will be understood that in place of sodium sulfite we may employ any other water-soluble inorganic sulfite. In fact sulfite treatment of the crystals is not an essential step in our invention, which comprises the production of a substantially pure trinitrotoluene product from the acid-retaining material separated from the bulk of the tri-spent acid without the necessity for using and discarding hot wash waters.

The advantages of our invention will be apparent when the resultant savings are understood. In the manufacture of trinitrotoluene and its subsequent purification according to the methods of the prior art, the treatment of a molten mate-

rial with a number of hot water washes entails considerable loss because of the solubility of trinitrotoluene in hot water. Such wash waters are commonly passed into so-called catch boxes, where cooling is allowed to take place and the dissolved trinitrotoluene precipitates out. The installation of such catch boxes and their upkeep and occasional replacement are a matter of considerable expense and interfere with smooth operating procedures. Because of the acidity of the wash waters, deterioration of such apparatus is more rapid than would otherwise be the case. Since our invention avoids the necessity of discarding any hot water washes and, in its preferred embodiments, effects the neutralization of substantially all acidity, catch boxes may be eliminated and increased yields will result.

Our invention has been described at length in the foregoing. It will be understood that many variations in details of operations, amounts and kinds of materials used, and succession of steps may be employed without departing from the spirit of the invention. For instance, it is sometimes desirable to cool the slurry after the introduction of the alkaline sulfite and before filtering.

We intend to be limited only by the following patent claims.

We claim:

1. In the manufacture of trinitrotoluene and the preparation of a crystallized, substantially acid-free product: the steps which comprise separating the molten trinitrotoluene from the bulk of the spent acid, contacting the acid-retaining molten material taken directly from the separation step with alkali and an aqueous medium, cooling the mixture below the solidification point of the crude trinitrotoluene, and discarding aqueous liquid at a temperature substantially below said solidification point and only at such temperature.
2. In the manufacture of trinitrotoluene and the preparation of a crystallized, substantially acid-free product: the steps which comprise separating the molten trinitrotoluene from the bulk of the spent acid, treating the acid-retaining molten material taken directly from the separation step with water and cooling the mixture below the solidification point of the crude trinitrotoluene, neutralizing the mixture with alkali, and discarding aqueous liquid at a temperature substantially below said solidification point and only at such temperature.
3. In the manufacture of trinitrotoluene and the preparation of a crystallized, substantially acid-free product: the steps of separating the molten trinitrotoluene from the bulk of the spent acid, treating the acid-retaining molten material taken directly from the separation step with water, cooling the mixture below the solidification point of the crude trinitrotoluene, separating the crystals from the acid water, washing said separated crystals with sufficient water to remove the greater part of the acidity therefrom, and discarding aqueous liquid at a temperature substantially below said solidification point and only at such temperature.

FRANCIS STAPLETON CHAMBERS, JR.
